DESIGN FOR SCOTCH SUITINGS.

Design No. **11,187**, dated May 13, 1879

UNITED STATES PATENT OFFICE.

FREDERICK T. CHASE, OF WEBSTER, MASSACHUSETTS.

DESIGN FOR SCOTCH SUITINGS.

Specification forming part of Design No. **11,187**, dated May 13, 1879; application filed April 15, 1879.
[Term of patent 3½ years.]

To all whom it may concern:

Be it known that I, FREDERICK T. CHASE, of Webster, in the county of Worcester and State of Massachusetts, have originated and designed a Pattern for Scotch Suitings or other Fabrics, of which the following is a full, clear, and exact description, reference being had to the accompanying photographic illustration, making part of this specification.

My design is formed in the weaving of the goods, which may be made from Nos. $2\frac{1}{2}$ to $5\frac{1}{2}$ "double-and-twist" yarn, of such colors as may be preferred.

It consists of the faint rose or rosette A, in which the fibers of the yarn mostly radiate from a common center, said rosette being surrounded by the diagonal bars or stripes B B C C, forming a division between the rosettes, and with them covering the surface of the cloth.

The design being particularly adapted to Scotch suitings, (so called,) suitable colors may be used to produce the desired harmonious effect.

The bars B B C C, being continuous, bring the rosettes alternate with the crossing of the bars, so that the rosettes in each row stand opposite the spaces or crosses between those of the next, or in quincunx order. These parts are intended to form an unobtrusive figure, or, in other words, are not strikingly prominent, but, on the contrary, are only noticeable in particular lights, the radial position of the fibers of the rosettes with the crossing of the bars combining to give the appearance of a stripe passing through the center of the rosettes and the crossed junction of the bars B C.

What I claim as my invention is—

The design for Scotch suitings, consisting of the rosettes described, quincuncially arranged with the diagonal bars, as shown and described.

FREDK. T. CHASE.
